ABSTRACT

A combustion flash bulb ignited by means of a piezoelectric ignition in which, to protect the wall of the envelope, a separate tubular inner envelope is arranged in the envelope, said inner envelope being open at its end facing the lamp base and comprising the metal wool to be burned. In order to attenuate the shock wave occurring during the combustion in the inner envelope, said inner envelope comprises opposite to the open tube end a narrowed end in which an aperture is provided. The inner envelope is thin-walled and manufactured from a soft glass.

COMBUSTION FLASH BULB

The invention relates to a combustion flash bulb which comprises a hermetically sealed light-pervious outer envelope and a tubular inner envelope which is open at its end facing the lamp base, the space in the inner envelope communicating with the space in the outer envelope, a filling of an oxidizable metal and an ignition mechanism being present in the inner envelope, an oxygen-containing atmosphere prevailing inside the outer envelope. Such a combustion flash bulb is known.

In the known flash bulb an inner envelope of a vitreous material is used the coefficient of expansion of which is very low, for example, Vycor or Pyrex. By using such an inner tube of hard glass in which the ignition mechanism is present, it is avoided that red-hot particles which during the explosive combustion of the ignition mass which forms part of the ignition mechanism of the lamp are thrown away towards the inner wall of the outer envelope. On said wall of the outer envelope, such particles may give rise to the formation of shrinkage cracks as a result of which said outer envelope is considerably weakened. By using an inner envelope which intercepts said particles and consists of a material having a very low coefficient of expansion and which inner envelope will not break during firing the lamp, a protective layer of laquer which usually covers the outer envelope may in principle be omitted.

In the known combustion flash bulb a tubular inner envelope is used which is open at one end and is closed in the form of a dome at its other end which is present near the tipped-off end of the lamp. It has now been found that this construction exhibits a few drawbacks. First of all, during evacuating the lamp and filling it with oxygen a rather long evacuating and transporting paths, respectively, is introduced which is formed by the non-tipped-off end of the exhaust tube at the end of the lamp, the narrow space between the side walls of the inner and the outer envelope and the whole space of the inner envelope. This results in a longer evacuating time as compared with traditional combustion flash bulbs without an inner envelope. At the same time, due to the tolerances in diameter of the tube glass, a considerable spreading in the filling pressures of various lamps of the same manufacturing series will occur; the transporting path which is narrow as it is, is by no means constant over a series of lamps. This necessarily results in a series of lamps the ignition times and light efficiencies of which are by no means constant. Secondly, an inner envelope is used which should have a rather thick glass wall so as not to break during firing the lamp. As an example may be mentioned a wall thickness of approximately 1.4 mm. It will be obvious that just for miniature flash bulbs a choice of a proportionally thick-walled inner envelope adversely influences the available effective lamp contents. While maintaining the external lamp dimensions, such a lamp will show a smaller luminous efficiency with the same choice of oxidizable metal, ignition mechanism, material of the outer envelope. A further drawback of the known combustion flash bulb is that the shock wave which is formed during the ignition and combustion of the oxidizable metal and which propagates in the inner envelope will produce large pressure differences between the space inside and outside the inner envelope.

velop. The inner envelope which is forced against the lamp base by spring action will then suddenly be lifted as a result of which said shock wave will reach the space around the inner envelope shockwise so that there is a possibility of explosion of the outer envelope.

It is the object of the present invention to mitigate the above drawbacks by providing a combustion flash bulb according to the above-described type which is characterized in that the inner envelope, at its narrowed and remote from the lamp base, comprises an aperture the cross-section of which calculated at right angles to the longitudinal axis of the lamp is at most 30 percent of the surface bounded by the inner wall of the inner envelope. By using an inner envelope having the above aperture at the narrowed end remote from the lamp base it is achieved that on the one hand the evacuation and filling path during the manufacture of the lamp is considerably reduced with all the advantages involved, and on the other hand the above-mentioned shock wave can propagate, via said aperture, in the space outside the inner envelope and will hence be strongly attenuated. As a result of this an inner envelope can be chosen to consist of a proportionally thin-walled material (wall thickness, for example, 0.25 mm) which need no longer consist of hard glass. It even does not matter when the inner envelope is destroyed during the combustion of the oxidizable metal. As a material for the inner envelope may be chosen, for example, the rather readily workable lime glass.

The dimension of the said aperture is chosen to be so that no red-hot particles of the ignition mass occurring in the ignition mechanism can emerge through said aperture and reach the normally weaker top part of the outer envelope. On the other hand, said aperture should be chosen to be so that the oxidizable metal which may be in the form of very narrow strips of zirconium-containing material, does not emerge through said aperture to in the exhaust tube at the lamp top during the manufacture of the lamp.

By choosing said inner envelope to consist of a thin-walled tubular material, a larger filling of said envelope can be obtained, for example, while maintaining the internal dimensions of the outer envelope.

According to an embodiment of the flash bulb according to the invention, in which the length is at least 3 times the inner diameter and in which the ignition mechanism is near the lamp base, the inner envelope is movable in the outer envelope in the axial direction, the ignition mechanism being surrounded by the inner envelope in the two extreme axial positions of the inner envelope. It is just in this type of slim flash bulbs that the evacuating and filling path, respectively, for the oxygen-containing gas is very long; the above-mentioned drawbacks then become particularly prominent. It has been found that the inner envelope should remain slightly movable in the outer envelope but in such manner that the tubular inner envelope always surrounds the ignition paste or the like, which forms part of the ignition mechanism. In particular, the distance between the side walls of the inner envelope and the outer envelope should preferably be chosen to be as small as possible.

According to another embodiment, the oxidizable metal accommodated in the inner envelope is kept

spaced apart from the ignition mechanism by an adhesive. A few drops of water glass have proved to be a reasonable solution.

When according to a final embodiment of the lamp according to the invention an inner envelope is manufactured from a blue-colored vitreous mass, the outer blue layer of laquer which is usually provided on the outer envelope may even be omitted.

The invention may be applied to various types of combustion flash bulbs. It may be used for lamps which are operated with a low voltage source or with a high voltage source by means of a piezo-electric ignition.

In order that the invention may be readily carried into effect, one embodiment thereof will now be described briefly with reference to the drawing.

The drawing shows a combustion flash bulb which comprises a tubular outer envelope 1, a lamp base 2 and a tip 3 which is obtained by sealing an exhaust tube 4. Two current conductors 5 and 6 are sealed in the lamp base 2 and terminate in a cup-shape cavity 7 which is present in a raised base portion 8. An ignition mass 9 which forms part of an ignition mechanism for the lamp is present in said space. A clew of oxidizable metal, for example zirconium wool, is denoted by 10. The lamp is filled with approximately 9 atm. oxygen. The dimensions of the lamp are: outer diameter 6 mm, inner diameter 5 mm, height 24 mm.

The ignition of said lamp takes place by the short-lasting application of a high voltage from a piezo-electric voltage source, as a result of which break-down by the ignition mass occurs succeeded by a current passage in which the thermal energy necessary for starting the explosive combustion is produced in the ignition mass 9. For this type of ignition reference is made to the Dutch published Pat. application No. 6,613,815.

A tubular inner envelope 11 of thin-walled material (wall thickness 0.3 mm) is arranged with some amount of play in the envelope 1 (a = at most 0.5 mm). This inner envelope 11 manufactured from lime glass is arranged in the outer envelope so as to be slightly movable and that in such manner that said inner envelope always surrounds the ignition mass 9 in its two extreme axially moved positions. This inner tube intercepts the thrown-away red-hot particles during the ignition of the ignition mass 9 which particles, in the absence of said envelope 11, would be thrown against the outer envelope and might give rise there to a considerable weakening and even fracture of the envelope 1. So the envelope 11 may be considered as a particle shield.

At its end remote from the lamp base 2, the inner envelope 11 comprises an aperture 12 the diameter of which is 1 mm.

This aperture 12 is a contribution that in spite of the

55

presence of the envelope 11 on the one hand the lamp vessel 1 can easily be evacuated in all places of its contents and be filled with an oxygen-containing atmosphere. Furthermore, upon ignition of the lamp and the combustion of the metal wool 10, the shock wave moving in the longitudinal direction of the envelope 11 will be guided through said aperture 12 to the space between the envelopes 1 and 11 as a result of which said shock wave is attenuated.

10 Furthermore, during the manufacture of the lamp the dome-shaped end of the inner envelope 11 with its aperture 12 holds the metal wool 10 at a distance from the exhaust tube 4.

15 The oxidizable metal 10 is furthermore kept spaced apart from the ignition mechanism by a suitable adhesive. This may consist of a few drops of water glass which are deposited in the wide part of the inner tube which is held with its aperture 12 downwards and in which a clew of metal wool is pressed.

20 If desirable, the inner envelope 11 may be formed from a blue-colored vitreous mass.

What is claimed is:

1. A combustion flash bulb which comprises a hermetically sealed light-pervious outer envelope and a tubular inner envelope which is open at its end facing the lamp base, the space in the inner envelope communicating with the space in the outer envelope, a filling of an oxidizable metal and an ignition mechanism being present in the inner envelope, an oxygen-containing atmosphere prevailing inside the outer envelope, wherein the inner envelope, at its narrowed end remote from the lamp base, includes an aperture the cross-section of which calculated at right angles to the longitudinal axis of the lamp, is at most 30 percent of the surface bounded by the inner wall of the inner envelope.

25 2. A combustion flash bulb as claimed in claim 1 of which the length is at least 3 times the inside diameter and in which the ignition mechanism is present near the lamp base, wherein the inner envelope is movable in the outer envelope in the axial direction, the ignition mechanism being surrounded by the inner envelope in the two extreme axial positions of the inner envelope.

30 3. A combustion flash bulb as claimed in claim 2, wherein the clearance between the side walls facing each other of the inner envelope and the outer envelope is at most 0.5 mm.

35 4. A combustion flash bulb as claimed in claim 1, wherein the oxidizable metal present in the inner envelope is kept spaced apart from the ignition mechanism present near the lamp base by a suitable adhesive.

40 5. A combustion flash bulb as claimed in claim 1, wherein the inner envelope is manufactured from a blue-colored vitreous mass.
